UNITED STATES PATENT OFFICE.

WILLIAM GILLIS, OF PARSONS, KANSAS, ASSIGNOR OF TWO-THIRDS TO
WILLIAM O'HERIN AND CHARLES W. WELLER, BOTH OF SAME PLACE.

SPARK-ARRESTER.

SPECIFICATION forming part of Letters Patent No. 377,485, dated February 7, 1888.

Application filed May 26, 1887. Serial No. 239,410. (No model.)

To all whom it may concern:

Be it known that I, WILLIAM GILLIS, of Parsons, Kansas, have made a new and useful Improvement in Spark-Arresters for Locomotives, of which the following is a full, clear, and exact description.

The improvement relates to the means for promoting the fuel-combustion and arresting the escape of sparks, substantially as shown in the annexed drawings, making part of this specification, and exhibiting the most desirable mode of carrying out the improvement, in which—

Figure 1 is a vertical longitudinal section of that portion of a locomotive with which the improvement is immediately connected, the section being on the line 1 1 of Fig. 2, which in turn is a vertical cross-section on the line 2 2 of Fig. 1; and Fig. 3 is a horizontal section on the line 3 3 of Fig. 1, the parts within the shell of the boiler being in plan view.

The same letters of reference denote the same parts.

In locomotives heretofore constructed it has been customary to divert the course of the products of combustion, after escaping from the boiler-flues, into the lower part of the smoke-arch, and thence upward through a netting into the stack; but in doing this the practice has been to lead an imperforated deflection-plate from the flue-sheet at a level immediately above the boiler-flues, said deflection-plate extending forward horizontally, or thereabout, past the exhaust-nozzles, and thence downward toward the bottom of the smoke-arch, and the netting is extended from the deflection-plate, at or near where the deflection-plate is turned downward, forward horizontally, or thereabout, to the forward end of the smoke-arch. In a locomotive having its smoke-arch thus divided and its smoke-currents thus directed the exhaust acts so directly upon the boiler-flues as to cause a considerable portion of the fuel to be drawn in a semi-consumed condition through the flues and into the smoke-arch. So rapidly does this occur that, to give a practical illustration of the difficulty, in a run of fifty miles the smoke-arch of a large locomotive will be-

come filled with solid matter, principally coke, up to the lower edge of the diaphragm, and progress of the locomotive is consequently arrested until the matter has been removed from the smoke-arch. To overcome this difficulty, to promote the combustion of the fuel in the firebox of the locomotive, and to arrest the escape of sparks from the stack is the aim of this improvement, which consists, mainly, in extending the space inclosed between the flue-sheet and the deflection-plate considerably above the level of the boiler-flues, and preferably quite to the top of the boiler-shell, and thereby providing a space considerably larger across vertically than the area of the combined flue ends, and by reason of such enlarged space preventing the exhaust from acting so directly upon the boiler-flues as to draw the fuel in an unconsumed condition through the flues.

In the drawings, A represents the forward end of a locomotive-boiler of the ordinary form.

B represents the customary pipe through which the live steam is supplied from the boiler through the nigger-head b and steam-pipes b' b' to the cylinders C C; but a single flue, D, Fig. 1, is shown—namely, one of the topmost row, the lower ones it not being necessary to show, as their construction and relative arrangement are well understood.

E represents the flue-sheet, F represents the smoke-arch, G G represent the exhaust-nozzles, and H represents the smoke-stack, all which named parts are of the usual form.

I represents the imperforate deflection-plate. Instead of starting it from the flue-sheet E at the level of the topmost flues, D, it connects with the shell f of the smoke-arch at the top thereof, as shown, and thence it extends downward and forward in front of the steam-pipes b' b', but shaped at i to provide for the upper end of the exhaust-nozzles G, which terminate in front of the deflection-plate. About midway vertically in the smoke-arch the deflection-plate is extended forward past the exhaust-nozzles, substantially as shown at i'. From this last-named point an imperforate diaphragm, i'', extends downward toward the bottom of the smoke-arch, but leaving an opening, f', beneath the diaphragm, through

which the products of combustion can pass to the front of the diaphragm into the space J, formed in the smoke-arch beneath the netting K, which extends from the part i' upward and forward to the shell of the smoke-arch forward of the smoke-stack, substantially as shown. The operation is as follows: The draft created by the exhaust-steam acts upon the space L between the flue-sheet E and the deflection-plate and diaphragm. By reason of the space being more extensive transversely than the area of that part of the flue-sheet occupied by the flues D the action of the draft upon the flues D is modified, and to such an extent that in the place of the lower portion of the flues becoming choked with particles drawn from the fire and the smoke-arch being filled up to the diaphragm, as hitherto has been the experience with locomotives whose deflection-plate connects with the flue-sheet in the vicinity of the topmost flues, the flues all remain open and practically no sediment collects in the smoke-arch, and hence, as indicated in the drawings, there is no provision made for reaching the interior of the smoke-arch for cleaning purposes. The lower portion, i^3 , of the diaphragm is made vertically adjustable in the customary manner. An additional feature of the netting is making toward its upper end a narrow opening, k, formed by a space left between the two parts of the netting K, Fig. 1—say three-eighths of an inch wide—for the purpose of influencing the draft toward the upper end of the netting, and thereby causing such particles as may find their way into the space beneath the netting to be drawn upward against the netting and thus more effectually abraded, broken up, and pulverized before es-

caping into the stack. The opening k is formed by making the netting in two parts, k' and k^2 , and interposing blocks k^3 of the thickness of the width of the slit k at the line of union of the parts k' and k^2 .

An additional advantage accruing from the improvement is its adaptability to many varieties of locomotives, to the old style, and also to the extended smoke-arch. It, further, can very readily and inexpensively be placed in position.

By extending the diaphragm horizontally forward at or near the top of the exhaust-pipes, and thence downward in front of the exhaust-pipes, as shown, the cost of constructing the diaphragm and of keeping it in repair is materially reduced.

55 I claim—

1. The combination, in a smoke-arch, of the imperforate deflection-plate, the exhaust-nozzles, and the netting K, said netting having an opening, k, formed by the space between the two parts of the netting, as described.

2. The combination, in a locomotive smoke-arch, of the steam-pipes, the deflection-plate and diaphragm, and the exhaust-nozzles, said diaphragm and deflection-plate starting from the top of the arch forward of said steam-pipes and extending downward and forward of them, but in the rear of the upper end of the exhaust-nozzles, thence horizontally forward past the exhaust-nozzles, and then downward toward the bottom of the smoke-arch, as described.

70 Witness my hand.

WILLIAM GILLIS.
